MANUAL CALCULATING DEVICE
Gottwill Reinholt, Bundesallee 177, Berlin-
Wilmersdorf, Germany
Filed Apr. 27, 1962, Ser. No. 190,760
20 Claims. (Cl. 235—80)

My present invention relates to a manually operable calculator adapted to be designed as a pocket-size instrument. This application is a continuation-in-part of my copending application Ser. No. 657,519, filed May 7, 1957, now abandoned.

The general object of my invention is to provide a miniature calculating device which, in spite of its compact size, accommodates a large number of digits for the performance of any of the four basic arithmetic operations, i.e. addition, subtraction, multiplication and division.

Another object of this invention is to provide an instrument of this type in which all the above operations can be carried out by manipulation of the same limited number of relatively movable parts.

A further object of the invention is the provision of a calculating device which can be conveniently combined with a pen, pencil or similar portable accessory normally carried by the user.

A principal feature of my present invention resides in the provision of two nested elongated members, i.e. a shaft and a surrounding sleeve, which are relatively rotatable and axially slidable and of which the outer one, i.e. the sleeve, carries a series of links selectively settable to indicate a digital value by the rotary entrainment of a digit wheel which is mounted on the inner member or shaft and whose digital markings are viewable through a window in the sleeve. The shaft, for convenience of handling, preferably projects endwise beyond the sleeve and may be shaped at its projecting extremity as a pen holder, pencil or the like. The links, according to a more specific feature of the invention, are in the shape of double-armed elements or angles which are swivelably journaled in cutouts of the sleeve wall and form an arcuate array over part of the periphery of the sleeve, each angle having one arm which in its withdrawn or inoperative position projects outwardly for engagement by a surrounding setting ring having an undercut portion whereby, upon rotation of the ring around the sleeve, these outwardly projecting arms of a selected number of angles will be consecutively depressed so that the other, inner angle arms project inwardly for entrainment of the digit wheel through the intermediary of suitable transmission means within the sleeve. The transmission means may comprise a holder nonrotatably mounted on the shaft, the holder carrying an eccentric pinion which meshes with gear teeth on the digit wheel and has its own teeth positioned for engagement with the operatively displaced angles.

In order to be able to perform multiplications and divisions as well as additions and subtractions on my miniature calculator, I divide the sleeve thereof into a totalizer section and a counter section each containing a number of digit and counting wheels, respectively, depending upon the number of digital positions or decades of the largest product or dividend and the largest multiplier or quotient to be handled. The wheels of the two sections are substantially identical, yet only those of the totalizer section are stepped by the aforementioned links whereas those of the counter section are advanced, in respective axial sleeve positions, by a fixed internal projection on the sleeve to count the number of sleeve revolutions. The digit wheels of the totalizer section, moreover, are provided with tens-transfer means for entering a decimal carry from a lower denominational order in a higher one; such transfer means may include, according to still another feature of the in-

2

vention, a stepping member axially displaceable in the sleeve wall adapted to be cammed, preferably by a slide carried on the aforementioned pinion holder co-operating with a setting disk on the digit wheel of the next-lower denominational order or decade, to advance the higher-order digit wheel by one unit upon rotation of the sleeve through a certain angular position relative to the shaft. These angular positions, staggered in peripheral direction for successive decades as is known per se, are advantageously distributed over one half of the sleeve periphery while the entraining links or angles are disposed along the other half thereof. In order to maintain the desired sequence between the stepping of a digit wheel and the transfer of a tens carry, each digit wheel is subdivided into two axially juxtaposed annular zones with separate rows of digital markings 0—9, the two zones of each wheel being relatively staggered by 180° whereby subtractions and divisions will have zero positions diametrically offset from those used for additions and multiplications. The sleeve may be indexable for this purpose in a number of axially spaced pairs of decadic positions, each position pair consisting of a left-hand and a right-hand position of which one aligns the sleeve windows with the rows of digital markings relating to addition and multiplication whereas the other exposes the rows intended for subtraction and division.

The above and other objects, features and advantages of my invention will become more apparent in the following detailed description of a preferred embodiment, reference being made to the accompanying drawing in which:

FIG. 1 is an elevational view of a calculating device according to the invention;

FIG. 2 is a perspective view of one side of a sleeve forming part of the calculator of FIG. 1;

FIG. 3 is a perspective view of the other side of the sleeve;

FIG. 4 is a developed plan view of the sleeve of FIGS. 2 and 3;

FIG. 5 is a fragmentary perspective illustration (parts broken away) of the totalizer and counter sections of the calculator with the associated wheel assemblies shown in exploded view;

FIG. 6 is a cross-sectional view on a larger scale, taken on the line VI—VI of FIG. 1;

FIG. 7 is a similar cross-sectional view taken on the line VII—VII of FIG. 5;

FIG. 8 is a fragmentary sectional view of the totalizer section, showing two adjacent digit wheels thereof;

FIG. 9 is an exploded perspective view of one of the digit wheels and associated elements of FIG. 8;

FIG. 10 is an enlarged cross-sectional view taken on the line X—X of FIG. 1;

FIG. 11 is a perspective detail view illustrating one of the links visible in FIG. 10; and

FIG. 12 is a fragmentary perspective view of the totalizer section with part of a setting ring thereof broken away.

Reference will first be made to FIG. 1 for a description of the external appearance of my pocket-size calculator. The device comprises a stem 1, adapted to receive at its free end a writing implement such as a pen point 52 shown in dot-dash lines, which projects from an elongated sleeve 4 and is divided into a totalizer section A and a counter section B. A thimble 47a, formed with a longitudinal slot 48a, and a ferrule 47b, having a similar slot 48b in alignment with the slot 48a, are fixedly positioned on opposite ends of the sleeve 4 and form between them a peripheral gap occupied by a series of digital setting rings 23. The slots 48a and 48b register with windows 18a and 18b in the sleeve proper, a window 18a appear-

ing also alongside a portion of each ring 23 terminating at an axially extending shoulder 123; the windows 18a in the totalizer section A and the windows 18b in the counter section B expose numerical markings on respective digit wheels 8a and counting wheels 8b. When shoulder 123 is rotated away from its window 18a, it exposes a scale 44 with similar digital markings 0-9; the associated window 18a constitutes the zero mark of that scale. Thus, as shown in FIG. 1, one or more wheels 23 may be displaced from their normal or zero position to register a finite numerical value, e.g. the number "210" as illustrated.

FIG. 5 shows the interior of the totalizer and counter sections A and B of FIG. 1. The digit wheels 8a and the counting wheels 8b, of which only one each is seen in that figure, are individually mounted on cylindrical bushings 10a, 10b carried by a profiled central shaft 2 which forms a rigid extension of the stem 1. Shaft 2 is shown provided with a flat face 5 which, however, does not impede the independent rotation of the several digit wheels by virtue of the interposition of the bushings 10a and 10b. Sleeve 4 is slidably and rotatably supported with reference to shaft 2 by being seated with its left-hand end directly on the stem 1 and engaging with its right-hand end a bearing disk 11 of like diameter; disk 11 is rigid with the sleeve and axially slideable on the shaft 2 to which it is confined by a pair of lock nuts 12.

An extension 53 of stem 1 is formed with a series of peripherally spaced pairs of annular grooves 3 and 3', these grooves being axially interconnected by diametrically opposite channels 49, 49' (see also FIG. 7) having depressions 50 and 50' respectively aligned with grooves 3 and 3'. A ball check 13 in sleeve 4, loaded by a flat spring 51, is receivable in any of the left-hand grooves 3 and right-hand grooves 3' of the several pairs as well as in the depressions 50, 50' for selectively indexing the sleeve in corresponding axial positions. It will be apparent that, in order to pass from one groove into another, the ball check 13 must be aligned with either of the channels 49, 49'; the rotary positions of sleeve 4 in which this occurs will be referred to hereinafter as the additive starting position (channel 49) and the subtractive starting position (channel 49').

Each digit wheel 8a and each counting wheel 8b is subdivided into two axially juxtaposed annular zones occupied by two sets of digital markings 46a, 46a' and 46b, 46b', respectively. The rows 46a and 46b, used in addition and multiplication, are staggered by 180° with reference to the corresponding rows 46a' and 46b' whereby the "0" mark of one row is next to the "5" mark of the adjacent row and vice versa. Moreover, the markings of rows 46a, 46a' and 46b all follow one another in the same ascending order whereas those of row 46b' are arranged in the opposite or descending order. The angular spacing of ball check 13 and windows 18a and 18b is so chosen that, with the wheels in a reference position illustrated in FIGS. 1 and 5, the "0" marks of rows 46a and 46b appear in the windows 18a, 18b with the sleeve 4 in its additive starting position (ball check 13 in one of the depressions 50) whereas the "0" marks of rows 46a' and 46b' will be visible when the sleeve occupies its subtractive starting position (ball check 13 in one of the depressions 50').

As best shown in FIGS. 2-4, the sleeve 4 exhibits besides windows 18a, 18b and ball check 13 a multiplicity of cutouts 19 interleaved with the engraved scales 44; elongated slots 14a and 14b extending axially just below the windows 18a and 18b respectively; shorter recesses 39 and 39' arranged in two intersecting diagonal rows on the side of the sleeve not occupied by the cutouts 19; and a lug 21 projecting inwardly from a location in line with the diagonal row of recesses 39. A pair of dampers 16a and 16b, pivotally journaled in slots 14a and 14b, respectively, are normally held withdrawn in these slots by means of springs 15 (see FIG. 6); pins 17a and 17b, fixed to the

dampers 16a and 16b, project outwardly through ports 117a, 117b (see FIGS. 1 and 6) in the tubular sleeve attachments 47a, 47b and may be manually pushed inwardly to occupy a position shown in dot-dash lines in FIG. 6 in which they can engage a lug 6a, 6b respectively projecting from either wheel 8a, 8b. Rotation of sleeve 4 to the position shown in FIG. 1, with pins 17a and 17b held depressed, will clear the totalizer and counter sections A and B by restoring the digit and counting wheels to their aforementioned zero setting.

Each of the wheels 8a, 8b is rigid with a respective central gear 30a, 30b whose teeth are resiliently engaged by a pair of axially deformed radial arms of an associated indexing disk 7a, 7b which is nonrotatably mounted on the profiled shaft 2. The wheels are thus yieldably maintained either in their zero position or in a numerical position into which they can be displaced through the intermediary of transmission means including pinions 29a, 29b respectively in mesh with their gears 30a, 30b. The pinions 29a, 29b are eccentrically journaled, by means of pins 31a and 31b (FIGS. 5, 9 and 10), on respective holders 9a and 9b which are nonrotatably supported on shaft 2 next to the indexing disks 7a and 7b. The lug 21 is alignable with the pinion 29b of any counting wheel 8b upon engagement of ball check 13 with either groove 3, 3' of a respective pair; in the position of FIG. 1, for example, the ball 13 registers with the leftmost groove 3 of FIG. 5 to align the lug 21 with the pinion 29b of the extreme left-hand or highest-order counting wheel 8b.

The cutouts 19, which are peripherally arrayed in as many groups of nine as there are setting rings 23 on the sleeve 4, have swingably lodged therein respective angular links 20 whose outer arms are normally urged outwardly, as illustrated in FIG. 10, by associated flat springs 45 (see also FIG. 11) having shoulders 145 bearing upon the outer periphery of sleeve 4. The several setting rings 23, respectively associated with the arcuate rows of angles 20, have an inner periphery 24 of small radius, closely hugging the outer surface of sleeve 4 on which they are rotatable, and are undercut to form an inner surface 26 of larger radius which clears the outer arms of the angles 20 in their outwardly projecting position. In this position the inner arms of the angles are withdrawn into the sleeve 4 and out of the path of the pinion 29a with which they are axially aligned, it being noted that the angles are wide enough to maintain this alignment even when the sleeve 4 is shifted from a "positive" axial position (ball check 13 registering with any groove 3) to the associated "negative" axial position (grooves 3') or vice versa. When the ring 23 is rotated to overlie one or more cutouts 19 with its small-radius periphery 24, it consecutively depresses the corresponding angles 20 so that their inner arms project inwardly into the path of the pinion 29a. It will be noted from FIG. 10 that each ring 23 is provided with a ball check 27 engageable with any one of ten peripherally spaced depressions 28 in sleeve 4 associated with this ring; thus the ring is maintained in its selected position relative to sleeve 4 when the latter is turned around the shaft 2. In the course of such sleeve revolution the operatively displaced angles 20 will successively advance the pinion 29a and the gear 30a in mesh therewith so that the associated digit wheel 8a will be stepped through the selected number of angular positions and display a corresponding digital marking through the window 18a aligned with it.

The position of pinions 29a and 29b is so chosen, as will be apparent from FIG. 5, that their outermost teeth will register with the lugs 6a, 6b of the associated wheels 8a, 8b in their zero positions so as to be engageable by the inner edge of the depressed baffle 16a or 16b at the instant when the wheel has been set to zero by this baffle. Since the pinions 29a and 29b tend to rotate in opposition to the lugs 6a and 6b, this simultaneous engagement will automatically arrest the sleeve 4 when the desired zero setting has been attained.

The pinion holders 9a of the totalizer section A also form part of a transfer mechanism for entering a decimal carry from a lower in a higher denominational order. As best illustrated in FIG. 9, this transfer mechanism includes a slide 33 which is radially guided in the holder 9a and is indexable, by means of two notches 34, 134 alternately engageable by a spring 35 on the holder, in an inoperative and an operative position, respectively. Secured to each lower-order digit wheel 8a, on its left-hand side facing the slide 33 of the next-higher order, is a disk 36 bearing a single cog 37. Upon passage through a predetermined angular position, i.e. from "9" to "0" in the counterclockwise or additive sense (digit row 46a) and from "0" to "9" in a clockwise or subtractive sense (digit row 46a'), cog 37 cams aside a boss 38 on slide 33 which is thereby moved from its inoperative to its operative position within the limits imposed by its rectangular aperture 32 receiving the shaft 2. The recesses 39 and 39' of sleeve 4 have axially slidably therein, against the force of respective springs 41, individual stepping members 40, 40' such as the T-shaped member 40 shown in FIGS. 8 and 9. This member is normally maintained by its spring 41 out of line with the associated pinion 29a but can be cammed into alignment therewith by the beveled face 42 of the operatively positioned slide 33 upon being rotated past this slide in the second half of a sleeve revolution. The angular staggering of the several members 40 and 40' (see FIGS. 3 and 4) causes this camming action to occur consecutively, in the course of either adding or subtracting sleeve revolution (clockwise and counterclockwise), for the successive decades of the totalizer section A. Any member 40 or 40' cammed into alignment with its pinion 29a, as shown in FIG. 8, causes this pinion and the associated digit wheel 8a to take one unit step as the sleeve is rotated. A stud 43, engaging a lower camming surface 142 of slide 33 during additive (clockwise) rotation, or a similar stud 43' (FIGS. 3 and 4), coacting with an upper camming surface 142' of the slide during subtractive (counterclockwise) rotation, restores the slide 33 to inoperative position with the spring 35 snapping into its notch 34. As will be apparent from FIGS. 3 and 4, the "negative" stepping members 40' are axially offset from the "positive" members 40 so as to register with the associated slides when the ball check 13 is in one of the grooves 3' rather than grooves 3.

The several rows of markings 46a, 46a' and/or 46b, 46b' may be distinguished from one another, if desired, by different coloring or background.

The operation of the calculating device according to this invention will now be described:

Addition

With the sleeve 4 indexed in the rightmost groove 3 (second groove from the free end of extension 53), an augend of one to six digits is registered on the scales of the sleeve by the uncovering of respective markings thereof (e.g. as shown in FIG. 12) through rotation of the corresponding setting rings 23. Ball check 13 is now in the extreme right-hand depression 50 of channel 49, thus establishing the additive starting position of sleeve 4, and zeros appear in all the windows 18a, 18b as shown in FIG. 1. Next, sleeve 4 is rotated in an additive sense (i.e. clockwise) through a full revolution, i.e. until the ball 13 clicks again into its original depression, whereupon the augend will have been transferred to the digit wheels 8a and will be readable through the windows 18a. Now, an addend is registered on the scales 44 in the manner described for the augend, this action being followed by a further turning of the sleeve 4 through 360° whereby the numerical value appearing in windows 18a is augmented by the amount of the addend. In like manner any number of further numerical items may be added to those previously entered, the total being exhibited in the windows 18a after the sleeve 4 has been returned to its additive starting position.

To cancel the number stored in the totalizer section A, baffle 16a is depressed and a further revolution is imparted to the sleeve whereby the register constituted by the wheels 8a is cleared in the manner previously explained.

Subtraction

With the apparatus again in its additive starting position, the minuend is entered in the totalizer section A by the procedure described for the augend, i.e. with clockwise rotation of the sleeve. Next, the sleeve is given half a turn in the counterclockwise or subtractive sense until the ball 13 registers with channel 49' in the subtractive starting position; the sleeve is then axially shifted to the left by one groove spacing into "negative" position, i.e. until the ball 13 drops into the adjacent depression 50', whereupon the minuend previously appearing on digit rows 46a can be read on the adjoining digit rows 46a' now aligned with the windows 18a. The subtrahend is then registered on the scales 44, this being followed by a final subtractive rotation of the sleeve 4 whereby the difference becomes visible in the windows 18a. Further subtractions may be performed in the same manner.

Multiplication

The multiplicand is entered in the totalizer section A in the same manner as the augend and the minuend in the aforescribed operations. With the setting wheels 23 maintained in their adjusted positions, and with the sleeve 4 in the extreme right-hand "positive" position as described for the adding operation, the sleeve is rotated through as many revolutions as correspond to the units digit of the multiplier. When this units digit appears in the extreme right-hand window 18b of the counter section B, the sleeve 4 is axially shifted to the left by one decimal spacing (i.e. until ball 13 clicks into the next depression 50) whereupon the same sequence of rotation is performed for the tens digit of the multiplier. In this manner all the multiplier digits (up to five in the embodiment illustrated) are consecutively registered. When the appearance of the desired multiplier in windows 18b of counter section B is complete, the product is visible in the windows 18a of the totalizer section A.

Division

Again, as in the preceding instances, the first number (i.e. the dividend) is entered by an additive operation.

Next, after a reverse rotation through 180° as described for the subtracting operation, the divisor is registered on the sleeve scales 44 and the sleeve is axially shifted until its leftmost digit is aligned with the first or the second significant left-hand digit of the dividend, with the ball check dropping into one of the depressions 50', whereupon the sleeve 4 is rotated in a subtractive sense until the divisor is greater than the number appearing in corresponding windows 18b. The sleeve is then shifted to the right until ball 13 drops into another depression 50'. The same procedure is repeated for successive digits until finally, in the units position, a remainder smaller than the divisor is registered on the digit wheels 8a as seen through the windows 18a. At this point the quotient can be read on the wheels 8b through the windows 18b on the counter section.

The counterclockwise rotation of the sleeve through 180° in a division or subtraction operation is necessary in order to establish a position symmetrical to that shown in FIG. 10 for the pinions 29a, the angles 20 and the stepping members 40, 40'. This insures that in each case the digit wheels 8a will be advanced by the setting rings 23 in the first half of a revolution while the tens transfers, if any, will additionally step these wheels in the second half.

Having described a preferred embodiment, I wish it to be understood that modifications may be made therein without departing from the spirit and scope of the invention as defined in the appended claims.

I claim:

1. In a calculating device, in combination, a shaft, an elongated sleeve coaxially supported on said shaft with freedom of relative rotation, an array of angularly spaced links each individually displaceable on the inner periphery of said sleeve between an operative position and a withdrawn position, manually settable control means on said sleeve selectively engageable with any number of consecutive ones of said links for adjusting them to said operative position thereof, a freely rotatable digit wheel on said shaft within said sleeve aligned with said array of links, transmission means within said sleeve coupled with said wheel and successively engageable by all of said links in operative position for stepping said wheel through a number of rotary positions corresponding to the number of operatively positioned links in the course of a revolution of said sleeve around said shaft, said sleeve being provided with a window, and a set of digital markings on said wheel individually viewable through said window in respective rotary positions of said sleeve for indicating different digital values.

2. The combination according to claim 1 wherein each of said links comprises a spring-loaded double-armed element swingably mounted in said sleeve, one of the arms of said element projecting into the interior of said sleeve in the operative position of said element, the other arm of said element projecting outwardly from said sleeve in said withdrawn position for engagement by said control means.

3. The combination according to claim 2 wherein said control means comprises a ring rotatable on said sleeve and provided with an undercut inner periphery for clearing all of said other arms of all of said elements in one rotary position and consecutively depressing said other arms upon rotation from said one rotary position into other rotary positions relative to said sleeve.

4. The combination according to claim 1 wherein said sleeve and said shaft are provided with co-operating indexing means for releasably maintaining said sleeve in any of said respective rotary positions.

5. The combination according to claim 1 wherein said shaft is provided with bearing means for said sleeve on opposite sides of said digit wheel.

6. The combination according to claim 5, further comprising an elongated holder projecting from said sleeve as a rigid coaxial extension of said shaft, one of said bearing means forming part of said holder.

7. The combination according to claim 1 wherein said transmission means comprises a gear rigid with said digit wheel, a holder nonrotatable on said shaft and a pinion on said holder in mesh with said gear, said pinion having teeth engageable by said links in their operative position.

8. The combination according to claim 7, further comprising a projection on said digit wheel and normally inoperative resetting means on said sleeve positionable for engagement with said projection, said pinion being disposed in the path of said resetting means for arresting same in a position in which said digit wheel displays a zero indication through said window upon entrainment of said projection by said resetting means.

9. A calculating device comprising a shaft; an elongated sleeve coaxially supported on said shaft with freedom of rotary displacement relative thereto; a plurality of axially separated digit wheels freely rotatable on said shaft within said sleeve, each of said wheels being provided on its periphery with a set of digital markings representing different numerical values from 0 to 9, the markings of each of said digit wheels constituting a respective decimal denomination of a total to be registered on said digit wheels, said sleeve being provided with a plurality of windows for the viewing in any of ten rotary wheel positions of a single marking of each digit wheel; a plurality of axially separated arrays of ten angularly spaced links each individually displaceable on

the inner periphery of said sleeve between an operative position and a withdrawn position, each of said arrays of links being axially aligned with a respective digit wheel;

manually settable control means on said sleeve selectively engageable with any number of consecutive ones of said links of each array for adjusting them to said operative position thereof;

transmission means in said sleeve for each of said digit wheels successively engageable with all the operatively positioned links of a respective array for stepping the associated digit wheel through a number of said rotary wheel positions corresponding to the number of links so positioned in the course of a revolution of said sleeve around said shaft whereby a totalizing operation can be carried out upon rotation of said sleeve about said shaft;

and transfer means on the inner periphery of said sleeve adjacent each of said digit wheels except the one of the highest decimal denomination for entering a decimal carry from a lower denomination in the next-higher one, said transfer means including a stepping member movable relatively to said sleeve, the digit wheels adjacent said transfer means being each provided with setting means effective in a predetermined rotary digit-wheel position for displacing said member from a normal ineffective position into an effective position aligned with said transmission means of the next-higher denomination whereby the transmission means of said next-higher denomination is stepped by one digital unit during a predetermined part of a sleeve revolution, said transfer means further including restoring means for returning said member to said normal ineffective position during a subsequent part of a sleeve revolution.

10. A device according to claim 9 wherein said stepping member is axially slidable on said sleeve, said setting means including a peripheral tooth on each of said adjacent digit wheels and a slide nonrotatably mounted on said shaft for radial displacement by said tooth from a normal position into camming engagement with said member whereby the latter is shifted toward the digit wheel of the next-higher denomination.

11. A device according to claim 10 wherein said restoring means comprises an internal projection on said sleeve for returning said slide to its normal position, and spring means effective upon such return for shifting said member away from said digit wheel of said next-higher denomination.

12. A calculating device comprising a shaft; an elongated sleeve coaxially supported on said shaft with freedom of rotary and axial displacement relative thereto;

co-operating indexing means on said shaft and said sleeve for yieldably retaining the latter in either of two axial positions;

a plurality of axially separated digit wheels freely rotatable on said shaft within said sleeve, each of said wheels being divided into two axially juxtaposed peripheral portions respectively provided with a first and a second set of digital markings representing different numerical values from 0 to 9, the markings of each of said digit wheels constituting a respective decimal denomination of a total to be registered on said digit wheels, said sleeve being provided with a plurality of windows for the viewing in any of ten rotary wheel positions of a single marking of said first and said second set of each digit wheel in a respective axial position of said shaft;

a plurality of axially separated arrays of ten angularly spaced links each individually displaceable on the inner periphery of said sleeve between an operative position and a withdrawn position, each of said arrays of links being axially aligned with a respective digit wheel;

manually settable control means on said sleeve selectively engageable with any number of consecutive ones of said links of each array for adjusting them to said operative position thereof;

transmission means in said sleeve for each of said digit wheels successively engageable with all the operatively positioned links of a respective array for stepping the associated digit wheel through a number of said rotary wheel positions corresponding to the number of links so positioned in the course of a revolution of said sleeve around said shaft whereby additive and subtractive calculations can be carried out upon rotation of said sleeve in a respective sense and in a respective axial position about said shaft; and transfer means on the inner periphery of said sleeve adjacent each of said digit wheels except the one of the highest decimal denomination for entering a decimal carry from a lower denomination in the next-higher one, said transfer means including a stepping member movable relatively to said sleeve, the digit wheels adjacent said transfer means being each provided with setting means effective in a predetermined rotary digit-wheel position for displacing said member from a normal ineffective position into an effective position aligned with said transmission means of the next-higher denomination whereby the transmission means of said next-higher denomination is stepped by one digital unit during a predetermined part of a sleeve revolution, said transfer means further including restoring means for returning said member to said normal ineffective position during a subsequent part of a sleeve revolution.

13. A device according to claim 12 wherein the stepping members of all of said transfer means are divided into two groups axially staggered relatively to each other for co-operation with the associated setting means in a respective axial position of said sleeve, said axially staggered stepping members being angularly offset from each other to a different extent in each of said transfer means, said stepping members being distributed over one peripheral half and said links being distributed over the opposite peripheral half of said sleeve.

14. A calculating device comprising a shaft; an elongated sleeve coaxially supported on said shaft with freedom of rotary displacement relative thereto, said sleeve being axially subdivided into a totalizer section and a counter section;

a plurality of axially separated digit wheels and at least one counting wheel freely rotatable on said shaft within said totalizer section and said counter section, respectively, each of said wheels being provided on its periphery with a set of digital markings representing different numerical values from 0 to 9, the markings of each of said digit wheels constituting a respective decimal denomination of a total to be registered on said digit wheels, said sleeve being provided on said totalizer and counter sections with a plurality of windows for the viewing in any of ten rotary wheel positions of a single marking of each digit and counting wheel;

a plurality of axially separated arrays of ten angularly spaced links each individually displaceable on the inner periphery of said totalizer section between an operative position and a withdrawn position, each of said arrays of links being axially aligned with a respective digit wheel;

manually settable control means on said sleeve selectively engageable with any number of consecutive ones of said links of each array for adjusting them to said operative position thereof;

transmission means in said totalizer section for each of said digit wheels successively engageable with all the operatively positioned links of a respective array for stepping the associated digit wheel through a number of said rotary wheel positions corresponding to the

number of links so positioned in the course of a revolution of said sleeve around said shaft whereby a totalizing operation can be carried out upon rotation of said sleeve about said shaft;

transfer means on the inner periphery of said totalizer section adjacent each of said digit wheels except the one of the highest decimal denomination for entering a decimal carry from a lower denomination in the next-higher one, said transfer means including a stepping member movable relatively to said sleeve, the digit wheels adjacent said transfer means being each provided with setting means effective in a predetermined rotary digit-wheel position for displacing said member from a normal ineffective position into an effective position aligned with said transmission means of the next-higher denomination whereby the transmission means of said next-higher denomination is stepped by one digital unit during a predetermined part of a sleeve revolution, said transfer means further including restoring means for returning said member to said normal ineffective position during a subsequent part of a sleeve revolution; and means including an internal projection on said counter section for stepping said counting wheel by one digital unit upon each revolution of said sleeve about said shaft.

15. A calculating device comprising a shaft; an elongated sleeve coaxially supported on said shaft with freedom of rotary displacement relative thereto, said sleeve being axially subdivided into a totalizer section and a counter section;

a plurality of axially separated digit wheels and a plurality of counting wheels corresponding to the number of said pairs of axial positions, said digit wheels and said counting wheels being freely rotatable on said shaft within said totalizer section and said counter section, respectively, each of said wheels being provided on its periphery with a set of digital markings representing different numerical values from 0 to 9, the markings of each of said digit wheels constituting a respective decimal denomination of a total to be registered on said digit wheels, said sleeve being provided on said totalizer section and said counter section with a plurality of windows for the viewing in any of ten rotary wheel positions of a single marking of each digit and counting wheel; a plurality of axially separated arrays of ten angularly spaced links each individually displaceable on the inner periphery of said totalizer section between an operative position and a withdrawn position, each of said arrays of links being axially aligned with a respective digit wheel;

manually settable control means on said sleeve selectively engageable with any number of consecutive ones of said links of each array for adjusting them to said operative position thereof;

transmission means in said totalizer section for each of said digit wheels successively engageable with all the operatively positioned links of a respective array for stepping the associated digit wheel through a number of said rotary wheel positions corresponding to the number of links so positioned in the course of a revolution of said sleeve around said shaft whereby a totalizing operation can be carried out upon rotation of said sleeve about said shaft;

transfer means on the inner periphery of said totalizer section adjacent each of said digit wheels except the one of the highest denomination for entering a decimal carry from a lower denomination in the next-higher one, said transfer means including a stepping member movable relatively to said sleeve, the digit wheels adjacent said transfer means being each provided with setting means effective in a predetermined rotary digit-wheel position for displacing said member from a normal ineffective posi-

tion into an effective position aligned with said transmission means of the next-higher denomination whereby the transmission means of said next-higher denomination is stepped by one digital unit during a predetermined part of a sleeve revolution, said transfer means further including restoring means for returning said member to said normal ineffective position during a subsequent part of a sleeve revolution;

and means including an internal projection on said counter section for stepping each of said counting wheels by one digital unit in a respective pair of axial sleeve positions upon each revolution of said sleeve about said shaft.

16. A calculating device comprising a shaft; an elongated sleeve coaxially supported on said shaft with freedom of rotary and axial displacement relative thereto, said sleeve being axially subdivided into a totalizer section and a counter section; co-operating indexing means on said shaft and said sleeve for yieldably retaining the latter in either of two axial positions;

a plurality of axially separated digit wheels and at least one counting wheel freely rotatable on said shaft within said totalizer section and said counter section, respectively, each of said wheels being divided into two axially juxtaposed peripheral portions respectively provided with a first and a second set of digital markings representing different numerical values from 0 to 9, the markings of each of said digit wheels constituting a respective decimal denomination of a total to be registered on said digit wheels, said sleeve being provided on said totalizer and counter sections with a plurality of windows for the viewing in any of ten rotary wheel positions of a single marking of said first and said second set of each digit and counting wheel in a respective axial position of said shaft;

a plurality of axially separated arrays of ten angularly spaced links each individually displaceable on the inner periphery of said totalizer section between an operative position and a withdrawn position, each of said arrays of links being axially aligned with a respective digit wheel;

manually settable control means on said sleeve selectively engageable with any number of consecutive ones of said links for each array for adjusting them to said operative position thereof;

transmission means in said totalizer section for each of said digit wheels successively engageable with all the operatively positioned links of a respective array for stepping the associated digit wheel through a number of said rotary wheel positions corresponding to the number of links so positioned in the course of a revolution of said sleeve around said shaft whereby additive and subtractive calculations can be carried out upon rotation of said sleeve in a respective sense and in a respective axial position about said shaft; transfer means on the inner periphery of said totalizer section adjacent each of said digit wheels except the one of the highest decimal denomination for entering a decimal carry from a lower denomination in the next-higher one, said transfer means including a stepping member movable relatively to said sleeve, the digit wheels adjacent said transfer means being each provided with setting means effective in a predetermined rotary digit-wheel position for displacing said member from a normal ineffective position into an effective position aligned with said transmission means of the next-higher denomination whereby the transmission means of said next-higher denomination is stepped by one digital unit during a predetermined part of a sleeve revolution, said transfer means further including restoring means for returning said member to said normal ineffective

position during a subsequent part of a sleeve revolution;

and means including an internal projection on said counter section for stepping said counting wheel by one digital unit upon each revolution of said sleeve about said shaft.

17. A device according to claim 16 wherein said first and second sets of digital markings of said digit wheels and said first set of digital markings of said counting wheel ascend in one sense of rotation and said second set of digital markings of said counting wheel ascend in the opposite direction of rotation.

18. A device according to claim 17 wherein said first and second sets of digital markings on each digit wheel are staggered by substantially 180°.

19. A calculating device comprising a shaft; an elongated sleeve coaxially supported on said shaft with freedom of rotary and axial displacement relative thereto, said sleeve being axially subdivided into a totalizer section and a counter section; co-operating indexing means on said shaft and said sleeve for yieldably retaining the latter in any of a plurality of pairs of juxtaposed first and second axial positions;

a plurality of axially separated digit wheels and a plurality of counting wheels corresponding to the number of said pairs of axial positions, said digit wheels and said counting wheels being freely rotatable on said shaft within said totalizer section and said counter section, respectively, each of said wheels being divided into two axially juxtaposed peripheral portions respectively provided with a first and a second set of digital markings representing different numerical values from 0 to 9, the markings of each of said digit wheels constituting a respective decimal denomination of a total to be registered on said digit wheels, said sleeve being provided on said totalizer and counter sections with a plurality of windows for the viewing in any of ten rotary wheel positions of a single marking of said first and said second set of each digit and counting wheel in a respective first and second axial position of said shaft;

a plurality of axially separated arrays of ten angularly spaced links each individually displaceable on the inner periphery of said totalizer section between an operative position and a withdrawn position, each of said arrays of links being axially aligned with a respective digit wheel;

manually settable control means on said sleeve selectively engageable with any number of consecutive ones of said links of each array for adjusting them to said operative position thereof;

transmission means in said totalizer section for each of said digit wheels successively engageable with all the operatively positioned links of a respective array for stepping the associated digit wheel through a number of said rotary wheel positions corresponding to the number of links so positioned in the course of a revolution of said sleeve around said shaft whereby additive and subtractive calculations can be carried out upon rotation of said sleeve in a respective axial position about said shaft;

transfer means on the inner periphery of said totalizer section adjacent each of said digit wheels except the one of the highest decimal denomination for entering a decimal carry from a lower denomination in the next-higher one, said transfer means including a stepping member movable relatively to said sleeve, the digit wheels adjacent said transfer means being each provided with setting means effective in a predetermined rotary digit-wheel position for displacing said member from a normal ineffective position into an effective position aligned with said transmission means of the next-higher denomination whereby the transmission means of said next-higher denomination

13

is stepped by one digital unit during a predetermined part of a sleeve revolution, said transfer means further including restoring means for returning said member to said normal ineffective position during a subsequent part of a sleeve revolution; and means including an internal projection on said counter section for stepping each of said counting wheels by one digital unit in a respective pair of axial

14

sleeve positions upon each revolution of said sleeve about said shaft.

20. A device according to claim 19, further comprising a holder projecting from one end of said sleeve as a rigid coaxial extension of said shaft, said indexing means including a portion of said holder provided with a plurality of annular grooves and a ball check on said sleeve receivable in said grooves.
